Henry B. Hastad
BY *Victor J. Evans*

ATTORNEY

UNITED STATES PATENT OFFICE.

HENRY B. HASTAD, OF BROOKLYN, NEW YORK.

ADJUSTABLE MIRROR.

1,249,081.

Specification of Letters Patent. Patented Dec. 4, 1917.

Application filed July 3, 1917. Serial No. 178,409.

To all whom it may concern:

Be it known that I, HENRY B. HASTAD, a citizen of United States of America, residing at Brooklyn, in the county of Kings and 5 State of New York, have invented new and useful Improvements in Adjustable Mirrors, of which the following is a specification.

This invention relates to adjustable mirrors and more particularly to a means for 10 retaining the same in one of a number of positions, whereby the user may adjust the same to the best advantage for the purpose in view.

Another object of the invention is the provision of a simple and efficient means of inducing the necessary friction to hold the mirror in its adjusted positions without resorting to the use of screws or other fastening devices of this character, said means being 15 automatic thus relieving the user of the necessity of operating any locking device after having positioned the mirror at the angle desired.

Another object of the invention is the provision of a device of the class described 20 which is simple in construction, thoroughly reliable and efficient in operation and inexpensive to manufacture.

Other objects and advantages will be readily apparent as the nature, purpose and operation of the device are better understood 25 from the following description and claims taken in connection with the accompanying drawings, of which:

30 Fig. 1, is a side elevation.

Fig. 2, is a similar view with parts in section.

Fig. 3, is a detail fragmentary section on the line 3—3, of Fig. 1, and

40 Fig. 4, is a detail perspective view of the plate.

Referring to the drawings by numerals, 10, designates a suitable base from which rises a standard 11, having an offset portion 12. 45 The mirror 13, is of any suitable construction and has secured to the rear face thereof an arm 14, which projects outwardly and is provided with an opening 15, in its free extremity. A disk 16, having a downwardly 50 extending stem 17, is secured to the offset portion 12, of the standard 11, by any suitable means. The disk 16, is vertically slotted as at 18, and is provided with a concen-

tric opening which receives a pivot 19, said pivot also being received by the aperture 15, 55 in the extremity of the arm 14, whereby the arm is mounted for pivotal movement. A cylindrical plate 20, is slidably mounted on the arm 14, and receives the latter in the centrally arranged opening 21, said arm being 60 preferably rectangular and the opening of like configuration. The plate is provided at its free extremities with the notches 22, the latter serving to embrace the stem 17, and act as stops for the plate when swung into 65 engagement with the stem. A coiled expandable spring 23, surrounds the arm 14, and is disposed between the mirror and the plate 20, in order to normally force the inner periphery of the latter into frictional contact 70 with the outer periphery of the disk, whereby the arm 14, is held against casual rotation on its pivot.

While I have shown and described a means for retaining the arm as applied to a mirror, 75 I wish it understood that the same may be adapted for other uses such as desk lamps and other articles of this character. I also wish it understood that changes and alterations that fall within the scope of the appended claims may be resorted to when desired.

Having thus described my invention what I claim is:

1. In a friction device of the character described comprising, a standard, a vertically slotted disk, an arm concentrically pivoted in said slotted portion of the disk, a semi-cylindrical plate slidably mounted on said arm, an object secured to the free extremity of the 90 arm and means for normally forcing the plate against the disk to retain the arm in its adjusted positions.

2. An adjustable mirror comprising, a vertical standard, a vertically slotted disk, 95 a stem extended downwardly from the disk and secured to the standard, an arm concentrically pivoted in the slotted portion of the disk, a semi-cylindrical plate slidably mounted on said arm, notches in the opposite extremities of the plate adapted for engagement with the stem, a mirror carried by the free end of the arm and an expandable spring surrounding the arm between the mirror and the plate. 100

3. In combination with a standard and a

pivoted mirror, of a means for retaining the latter in its adjusted positions, said means including a vertically slotted disk secured to said standard, an arm secured to the mirror and extended into the slotted portion of the disk, a concentrically arranged pivot extending from the disk and the free extremity

of the arm, a semi-cylindrical plate slidably mounted on the arm and means for forcing the inner periphery of the plate against the outer periphery of the disk. 10

In testimony whereof I affix my signature.

HENRY B. HASTAD.
